UNITED STATES PATENT OFFICE.

WILLIAM J. F. DAILEY, OF RIDGEWOOD, NEW JERSEY, ASSIGNOR OF ONE-HALF TO
PAUL J. WATROUS, OF PASADENA, CALIFORNIA.

RAZOR STROP.

1,407,190.

Specification of Letters Patent. Patented Feb. 21, 1922.

Application filed February 16, 1920. Serial No. 358,807.

To all whom it may concern:

Be it known that I, WILLIAM J. F. DAILEY, a citizen of the United States, and resident of Ridgewood, New Jersey, have invented 5 new and useful Improvements in Razor Strops, of which the following is a description, reference being had to the accompanying drawings, which are a part of this specification.

10 The present invention relates to certain new and useful improvements in razor strops and refers more particularly to a device of this character especially adapted for use with safety razor blades.

15 One object of this invention is to design a device to put a fine shaving edge on any safety razor blade and is constructed to form an endless strip for engagement around the hand in such a manner as to bring the strop- 20 ping portion thereof to the most convenient position.

Another object of the present invention is to provide a device of this character hav- 25 ing means for adjusting the same to the size of the user's hand.

With the above and other objects in view which will appear as the description pro- 30 ceeds, my invention resides in the novel construction, combination and arrangement 35 of parts substantially as hereinafter de- scribed and more particularly defined by the appended claims, it being understood that such changes in the precise embodiment of the hereindisclosed invention may be made as come within the scope of the claims.

In the accompanying drawing I have illus- 40 trated two complete examples of the physical embodiment of my invention con- 45 structed according to the best modes I have so far devised for the practical application of the principles thereof, and in which:

Figure 1 is a perspective view of my de- 45 vice depicting the same as positioned for use on the user's hand, the hand being shown by dotted lines.

Figure 2 is a perspective view of the de- 50 vice detached, and

Figure 3 is a perspective view of a slightly modified form of my invention.

50 My invention is designed to put a fine shaving edge on any safety razor blade, preferably of the flat type and is constructed of a strip of leather 5 having a strip of

elastic material 6 secured as at 7 to one end thereof and having a loop or eye 8 secured to its other end 9 through which the elastic strip 6 passes. The other end of the strip 6 has a fastener 10 secured thereto which may be of any desired construction and is designed to secure said other end of the strip in any desired position with reference to the medial portion thereof to retain the same in any adjusted position as will be readily apparent.

In that form of my invention depicted in 65 Figure 3 a strip 11 has one end secured to the end 12 of the strip 5 and has its other end 13 passed through a buckle or other fastening member 14 secured to the other end 15 of the strip 5, whereby the endless 70 strip or belt formed by the strips 5 and 11 may be readily adjusted to accommodate the device to fit the user's hand as will be obvious.

The strop is wrapped around one hand 75 of the user in such a manner as to bring the leather portion or strip 6 against the outside of the hand opposite the thumb and below the little finger. The razor blade is then held in the other hand between the 80 thumb and forefinger and is stropped up and down, slightly diagonally against the leather strip 5. It has been proved by microscopic tests of the efficiency of this de- 85 vice that the blade is sharpened and made far more effective as the natural curve of the leather around the side of the hand and the give of the strip 5 insures the engage- 90 ment of the entire edge of the blade with the strip at all times.

What I claim as my invention is:

1. A razor strop consisting of an endless strop engageable over the hand of the user and including a section of leather and a section of elastic material, said parts being 95 easily adjustable to different diameters.

2. A razor strop comprising a strip of leather, a strip of elastic material, and a buckle means for connecting the leather and the elastic material together to form an end- 100 less strop engageable over the hand of the user and easily adjustable to different diameters.

In testimony whereof, I affix my signature.

WILLIAM J. F. DAILEY.
